CONTAINER

Philip Zalkind, Bronx, N. Y.

Original application September 3, 1932, Serial No. 631,682, now Patent No. 1,946,516, dated February 13, 1934. Divided and this application September 21, 1933, Serial No. 690,360

16 Claims.

(Cl. 45—2)

My invention relates to novel casings and drawers adapted to be stacked to form a file cabinet or the like, and more particularly, relates to casings and cooperating drawers, which are collapsible and accordingly adapted to be shipped in knock-down condition.

Although containers or casings have heretofore been constructed of sheet material such as cardboard, corrugated board, and similar materials, these have been found to be deficient in rigidity, stability, load-carrying capacity, and facility in operating the drawer. And as to the last, particularly where attempt has been made to stack a plurality of casings each containing a loaded drawer. In such instances, the load in each casing affected all the casings below it, producing various degrees of bowing of side walls, distortion and binding at the open ends of the casings, making operation difficult, and seriously affecting the life and usefulness of such containers.

Accordingly, among the objects of my invention are to provide: a novel, inexpensive and rugged container or casing adapted for storing records and the like; means in a stack of individual casings for maintaining a predetermined geometrical configuration and dimension at the open edge or mouth of each casing; reinforcing or stiffening means at the open end or mouth of my novel casing construction; supporting means adapted to be interposed between the upper and lower walls of a container; metallic reinforcing means at the open end of collapsible casings; coacting means at the edges of open ends; a casing reinforced solely at the open end; a continuous load-carrying means in a stack of containers; reinforcing members at the open end of a collapsible container so constructed that the reinforcements on superposed casings are in engagement with each other causing the load in one casing to bear directly on the reinforcing member of the casings below, and means for aligning such reinforcing members to each casing. Other objects are to provide, in a collapsible casing construction of the character of material mentioned, means to prevent sway, rock or wobble; to construct such a novel device so that it may be manufactured to be shipped in a knock-down condition, of simple and easy assembly and erection by the user; to provide such novel containers and casings in knocked-down condition, thus adapted to lie substantially flat, requiring a minimum of space for shipment and storage, providing low cost, handling, marketing and distribution and reduced risk of damage before being put in use.

In using individual drawers and casings, ordinarily the casing tends to move with the drawer when an attempt is made to move the drawer out of or into its casing, due to friction between the loaded drawer and its casing.

Moreover, this difficulty becomes more serious when such casings and drawers comprise a stack, the danger then being to disrupt the stack.

I have discovered that by so mounting the casings with respect to each other that adjoining edges of the reinforcing members of adjacent casings are in engagement and in interlocked relation with each other, the total load from all of the drawers can be carried by the reinforcing members acting as an aligned unitary structure. In moving any one drawer from the casing, the load of all the other drawers is applied to and holds the casing back and permits the drawer to be readily removed.

Accordingly, a further object is to provide interlocking means in a stack of casings.

Other objects are to provide interlocking means cooperating between reinforcing members at the open end of casings mounted in a stack; means to align side walls, and end walls; means in cooperation with the reinforcing members to prevent the casings in a stack from sliding with reference to each other; means in a stack of open end casings for transmitting the load of each casing to the adjacent casing through metal connections; a casing, for cabinet drawers or containers as above described, constructed of material similar to that of the drawer, and having one end closed in any suitable manner and the edge portion of the other end or mouth reinforced by cooperating or interlocking strips, adapted to stiffen the mouth of the casing and prevent the material from fraying out, and, as occasion requires, to also form a rabbet at the opening of said container; to construct container casings of suitable sheet material in combination with reinforcing strips of such construction and so disposed that the container may be shipped in knocked-down condition and be readily assembled by the consumer; to provide means for locking or keying the metal reinforcements of a stack of casings together, to prevent said casings from sliding with respect to one another when they are stacked.

There are other objects and advantages of my invention which, together with the foregoing, will appear in the following detailed description of the invention in connection with the accompanying drawings, in which:

Figure 1 is a perspective view of a casing,

adapted to receive a drawer constructed like those illustrated in my parent application Serial Number 631,682, filed September 3, 1932, issued as Patent No. 1,946,516, Feb. 13, 1934 of which the present application is a division.

Figure 2 is a fragmentary view of the open end of a drawer casing having reinforcing strips on the inside thereof.

Figure 3 is a sectional view taken on line 3—3 of Figure 2, looking in the direction of the arrows and showing the manner in which lugs or abutments formed near the ends of the upper and lower reinforcing strips are employed to hold side reinforcing strips or posts in position.

Figure 4 is a sectional view taken on line 4—4 of Figure 2, including one entire vertical post.

Figure 5 is a view in perspective of a channel or reinforcing strip used in the casing shown in Figure 2.

Figure 6 is a blank or development of sheet material having strips on the front edge thereof and adapted to be folded to form the casing shown in Figure 2.

Figure 7 is a section taken on line 7—7 of Figure 2, and looking in the direction of the arrows.

Figure 8 shows a modified form of container having the front edge thereof reinforced with strip and post members adapted to be held in place by means of abutments and adhesive tape in such a way as to form a rabbet along the side walls at the mouth of the casing.

Figure 9 is a sectional view taken on line 9—9 of Figure 8, and looking in the direction of the arrows, showing the posts and upper and lower strips in operative position.

Figure 10 is a section taken on line 10—10 of Figure 9 and looking in the direction of the arrows.

Figure 11 is an enlarged detailed view showing the construction of the upright posts and adhesive material for securing the same to the casing.

Figure 12 is a perspective view of the upper and lower channel or stiffening strips shown in Figure 8.

Figure 13 is a blank or development formed of sheet material to which posts and stiffening strips are secured and from which a casing like that shown in Figure 8 may be made when the same are folded and secured in the proper position.

Figure 14 is a perspective view of a modified form of casing like that shown in Figure 8 in which the upright posts as well as the upper and lower stiffening strips are adapted to capture and slip over the edge of the material.

Figure 15 is a sectional view taken on line 15—15 of Figure 14 and looking in the direction of the arrows.

Figure 16 is a view in perspective of the blank from which a casing like that shown in Figure 14 may be made, shown just before being folded upon itself in position ready for shipment and with the posts in reverse position to adapt the casing to lie flat.

Figure 17 shows the manner in which a plurality of casings like that shown in Figure 14 may be placed one upon the other in a stack.

Figure 18 is a sectional view taken on line 18—18 of Figure 17, and looking in the direction of the arrows, showing the formation of corresponding cooperating grooves or slots in the reinforcing or stiffening strips at the front edge 75 of the casing adapted to receive a key to prevent

a plurality of stacked casings from sliding with respect to one another.

Figure 19 is a perspective view of the key shown in Figure 18.

Figure 20 is a view in perspective of a modified form of a casing having the front edge of the open end reinforced with metallic strips adapted to be secured by adhesive material carried on pads or fillers disposed in said strips.

Figure 21 is a sectional view taken on line 21—21 of Figure 20 and looking in the direction of the arrows.

Figure 22 is a view of a blank or development from which a casing like that shown in Figure 20 may be made, shown as about to be folded upon itself into position for shipment.

Figure 23 is a perspective view of a stiffening strip or channel for reinforcing the edge of the container shown in Figure 20, and the manner of carrying adhesive material, if desired, on a pad or filler disposed therein; and

Figure 24 is an assembled view of a casing and container or file drawer made in accordance with my invention.

Figure 25 is a detail of the wire interlock arrangement of Figure 14.

Referring now to the drawings, Figure 1 discloses one form of my casing and it will be noted that in general, the casing comprises a rectangular tube 31 with one end 32 left open and the other end 33 provided with closure flaps secured to each other in any suitable manner, as by tape, and the connected edges of the blank being secured together by any well known means, such for example, as the tape 34. The tube is formed of a blank substantially such as shown in Figure 6 suitably cut and scored.

My invention contemplates so forming the open end of a collapsible casing that its shape is not distorted by the load of the casing. For this purpose the front or open end 32 of the casing is reinforced by first turning extensions of the material on itself along a scored edge to form a layer 35. If it is desired to further increase the strength of the front or open end of the casing, the material may be again turned on itself to form a third layer as at 36. As will be obvious, this principle may be followed by regulating the number of layers to obtain any desired reinforcement.

The extensions may be turned into place, and may be secured to the adjacent wall of the casing, as by adhesive, staples, rivets, or any other suitable means. The reinforcing members may be simple extensions of their respective walls; or may be turned on themselves forming face to face layers, which may be secured to each other. It is preferred, however, that at least one pair, either the adjacent or opposing reinforcing members, be free from the adjacent walls of the casing so that when the casing is collapsed for purposes of shipment, these free reinforcing members may be turned outwardly on their scored edges, so that they protrude from the front edge of the casing. As is well known, the board most commonly used for such purposes is normally adapted to be collapsed on the scores without provision for undue pull or strain resulting from interposing a bulk at the scores between the adjacent sides which are in face to face relation.

If all the reinforcing members were to be turned inwardly and the casing collapsed, such interlying bulk at the common edges of the face to face wall members would normally be excessive and cause a rupture at these common connecting

lines. By permitting reinforcing members to remain in projecting or extended position when the container is collapsed, the risk or certainty of rupture or injury to the container from such interlying bulk is avoided.

Although I have disclosed the reinforced layers riveted to each other, I may, if desired, merely turn the layers on themselves without any securing means as illustrated in the top and right side reinforced members in Figure 1.

The utility of this container will now be obvious. Normally for shipment, the container is collapsed to form a substantially flat unit with two opposite or adjacent reinforced members turned outwardly depending on the manner of collapsing. It will be understood that the casing is collapsed on scorings so that an edge with a reinforcing member turned inwardly comes into face to face contact with an edge having its reinforcing member turned outwardly. Or, if preferred, all of the flaps may be turned outwardly when the casing is collapsed. In that case, none of the reinforcements are permanently secured to the walls of the casing. The upper and lower reinforcing members may be turned into place first and the side reinforcing members turned in to hold the former in place. The side reinforcing members are then held in place by friction. Or the reverse order of folding may be followed in which case the side walls are held in place by the upper and lower reinforcing members. The scorings and cuts in either case are suitably made to permit any preferred order of folding.

At the consumer's point, the collapsed container is first turned on its scored edges to form the tube as shown in Figure 1 and the outwardly projecting reinforced members 35 are turned on their scored edges into the position shown in Figure 1. Rear flaps are turned to closing position and secured, and the container is ready for use.

Referring now to Figure 2, I have shown a casing formed as the tube in Figure 1 with four sides, one closed end, and one open end. However, I provide a different form of reinforcing member for the open end of the casing, comprising metallic channels 41.

The channel 41 is shown in perspective in Figure 5, and as disclosed there, is substantially U-shaped with the edges turned inwardly to form lips 42 and 43. At the ends of the channel member 41, abutments are provided by projecting lugs 44 stamped out of the material.

The metallic U-shaped channel 41 is slipped over the flap 45 in Figure 3 with the lips 42 and 43 cutting into and gripping the material, as illustrated, to anchor the channel in place. The flap 45, thus seated inside the U-shaped channel is turned inwardly along its scored edge as illustrated in Figure 3. The upright channels 41 are mounted on their corresponding flaps in the same manner and are further held in place against the side walls and prevented from turning on their scored edges after the flaps have been turned inwardly on their scored edges, by the abutments 44 at the end of the top and bottom channel 41.

In this case, for shipment, before collapsing the container, at least two flaps with the channels secured thereto are first turned on their scored edges outwardly to permit ready collapsing.

In Figure 4, which is a cross section through one of the vertical posts 41 and including a cross section of portions of the top and bottom side

wall, there is shown the outside wall 31 with the adjacent layer of U metal 41 and flap 45 sandwiched between the two sides of the channel. A similar cross section appears for the horizontal upper and lower edge with the addition of the lugs 44.

Figure 6 shows in developed form the scored blank which is subsequently turned into the container shown in Figure 2. As shown, the blank is suitably scored and slotted as at 55 to form the four side walls 56 to 59. At the rear end there are provided flaps 51 to 54 which provide the closed end of the container and are secured in any well known manner. Metallic reinforcing members 41 slipped over and held in place on their respective flaps 45 in a manner already described in detail, are shown with alternate reinforcing members having lugs 44. As will now be clear, in the collapsed condition, all of the flaps with their reinforcing members may protrude from the open edge of the casing.

Although for purposes of illustration I have here shown a specific construction of metal reinforcement, it will be obvious that any other suitable construction coming within the principle of my invention which broadly contemplates the application of metallic reinforcing members to the open edges of the container, may be used. Thus, for example, I may use a sheet metal which may be secured by clamping, riveting, etc. to the flaps, as will be described in more detail hereinafter in connection with other modifications of my invention. Although I have here described specifically the use of metal reinforcing members, it will be obvious that the principle of my invention embodies the use of any stiffening or reinforcing material such as various fibers, plastics, wood, etc. which may be integral therewith and is applied adjacent to the edges.

Referring now to Figures 8 to 12, I have disclosed a modified form of my invention in which the reinforcing member is substantially channel-shaped and is secured by cloth or tape or any other suitable flexible medium. Two horizontal members of one construction are secured to the horizontal edges of the casing. Two vertical reinforcing members of a different construction are secured to the vertical edges of the casing.

As shown in Figure 12, in the horizontal reinforcing metal member 54, lugs 61 and 62 are stamped at right angles to each other. As will appear from the following, abutment 61 retains the associated vertical posts against the side walls and abutment 62 prevents the post from slipping out. Stampings 63 and 64 are also provided to form transversely positioned lugs for securing the reinforcing members to the wall.

As shown in Figure 11 the vertical reinforcing posts 60 are provided with a backing or filler 65 seated in the channel formed by the reinforcing member and the tape or cloth 66 is inserted between the backing 65 and the side 67 of the channel member and locked in position by the turned over edge 68 which pinches the material in position.

By moistening tape 66 before turning the post or channel into supporting position and thereafter turning the tape over the edge of the casing, it adheres to the edge and inner surface wall 70 of the casing, thus supplying a means for maintaining the channel as a support in predetermined position. The tape serves at the same time to give protection and a finished appearance to the edge of the container.

As will now be obvious, the horizontal reinforcing members 59 are slipped over their respective horizontal edges of the casing and permanently secured in position by lugs 63. These reinforcing members do not change their positions when the casing is collapsed.

When the casing is set up into its tube form, the vertical posts 60 are turned inward around their respective vertical edges of the casing and slipped over the abutments 61 and 62, abutment 61 pressing the associated parts against the side walls and the abutment 62 preventing their associated parts from slipping out.

It will now be clear from a comparison of Figures 1, 2, and 8 that generally the open edges of collapsible casings are provided with reinforcing members which are arranged so that they do not injure the scored edges when the casing is collapsed. As shown in the illustrations thus far given, all the reinforcing members may be secured to flaps extending from the casing edges, or two may be permanently secured to the edges without hindering collapsibility. Further combinations are obvious in view of the above.

This post and tape structure also provides means for forming, if desired, a rabbet by its position against the inner surface of the wall and set in from the front edge so that when the drawer of proper construction is slid into position, it will fit against the formed rabbet and provide a substantially dust proof container. It will be obvious that, if desired, the metal and tape structure may be used on all four edges of the casing.

As shown in Figure 9, the tape 66 is secured to the outside vertical walls of the casing in any suitable manner as, for example, by adhesive, stitching and the like with the reinforced channel normally protruding beyond the open edge of the casing as shown at the right end in Figure 8. The reinforcing member 60 constitutes the vertical posts through which the loads of the drawers above are transmitted to the next lower casing as will be described in more detail hereinafter in connection with a stack of casings.

Normally for shipment, the casing 70 (Figure 8) is collapsed with the two vertical posts 60 extending beyond the front edge of the casings as illustrated in connection with one of the vertical posts in Figure 8. At this time, the top and bottom horizontal reinforcing members 59 have been slipped into place and clamped in position. In addition the lugs 63 grip the material of the casing. When the casing is to be assembled, it is first turned to assume a tubular position. The rear flaps are secured to form a closed rear end. The vertical reinforcing posts 60 are turned around the edges of the casing and slipped over the lugs 61 and 62 which then lock these posts in position as described hereinbefore.

The developed view of the blank from which the casing is made is shown in Figure 13 and illustrates the reinforcing members 59 at the top and bottom edges of the blank with their lugs 61 and 62 at the ends and the lugs 63 and 64 to assist in gripping the walls to lock the reinforcing member in position. Vertical reinforcing posts 60 are shown secured to the tape material 66 and in turn are secured to the outside surface of the vertical panels.

Referring now to Figures 14 to 19, I have disclosed a further modification of my invention in which the reinforcing members 71 acting as vertical posts are adapted to be applied to the end edges of the wall with the outer edges 72 on the

outside of the casing wall and the bent portion 73 adjacent thereto in engagement with the edge 74 of the casing 75. The remaining portion 76 of the vertical post which is substantially channel or trough shaped extends into the inside of the casing wall and with the edge 77 forms a rabbet for the purpose described hereinbefore. The upper and lower reinforcing members 78 comprise simple U-shaped channel members which are slipped over the upper and lower edges of the casing and enclose near their ends one side of a right angle wire 79. Normally, the vertical posts 71 are mounted with the U-shaped channel portions 76 thereof on the outside of the casing as illustrated in Figure 16 for the purpose of permitting the casing to be collapsed; that is to say, the reinforced member is in reverse position. The wires 79 are then rocked about pivots formed at the ends of the edges 74 to lie against the adjacent edge 74 of the casing to form a substantially flat unit readily packed.

For purposes of assembling, the casing is first turned until the tubular formation of Figure 14 is obtained and the end of the wire 79 protruding from the upper and lower reinforcing members is rotated about its pivot until the wire lies in a line along the edges 74 as illustrated at the left edge in Figure 14. Vertical reinforcing posts 71 having previously been removed, are reversed in position and placed over the wire and adjacent edge, with its channel or post portion 76 on the inside of the casing wall.

For purposes of interlocking adjacent casings in a stack, the wire edge 79 protruding from the upper and lower channels is swung into position adjacent the vertical edge of the casing above and below this casing respectively and the posts of these respective casings are slipped over the wire of the casing below and the edge as illustrated in Figure 17. To permit the wires to cross each other, they may be formed with loops. This provides a secure interlock between casings to prevent the movement of one casing with respect to the other.

It will be noted at this time that because of the shape of the vertical posts 71 which comprise the bulging channel shaped section 76, the horizontal reinforcing members 78 along the upper and lower edge rest directly on the posts or to explain it otherwise, the posts provide supports for these horizontal reinforcing members. The load in the drawer is thus effectively applied to the lower horizontal reinforcing member. Through the horizontal member 78 the load is transmitted to the upper horizontal reinforcing member of the casing just below on which it rests and thence through the vertical posts thereof, on which the upper horizontal reinforcing member rests to the lower horizontal reinforcing member, etc. The load is thus carried through these reinforcing members to the base support.

It will thus be seen that the load of the drawers is substantially carried through these reinforcing members so that as a matter of fact, the casings themselves can be made of substantially much lighter and less expensive material than otherwise would be necessary.

Moreover, these vertical posts, as has already been explained, maintain an irreducible spacing between the horizontal reinforcements and thus define the dimension and shape of the opening of the casing preventing the load of the casings from causing the opening of the casing to buckle.

The right angle wires 79 interlock the vertical posts with the horizontal reinforcing members 75

giving rigidity to the open end of the casing to maintain a fixed shape and angle of the opening. When interlocked with adjacent casings, the vertical post of one casing is secured to the 5 horizontal reinforcement of the adjacent casing so that the movement of one with respect to the other is prevented, again giving rigidity to the open end. It will be obvious that the wires crossed from one casing to the next serve to 10 align the vertical posts and therefore the successive casings.

As shown in Figure 15, the corner wires may comprise a continuous piece with the ends turned into right angles, so that both ends turn together, and, as occasion may require, provide 15 additional stiffening by its length.

The affixing of such corner wires thus substantially assures elimination of the swaying or rocking, since the result is a metal to metal contact as distinguished from applying metal or similar bracing means in contact with the comparatively weak texture of material ordinarily used in constructing collapsible containers.

Intercrossing or adjacent wires in a stack as 25 described above, interlock containers, prevent their sliding with reference to each other, and serve also to align the vertical reinforcement channels end to end over each other, thus assuring greater load-carrying capacity in the stack 30 as a whole, particularly preventing the containers at the bottom of the stack from buckling or binding on their vertical open dimension, and maintaining a practically irreducible predetermined dimension to assure easy withdrawal and 35 replacement of the front wall of the drawer.

In Figure 18, I have shown a further alternative method for preventing the casings from slipping with respect to each other and for maintaining the vertical posts and the casings in 40 alignment. This view is a cross section taken through the upper and lower horizontal reinforcing members of adjacent casings, and as shown, the reinforcing members 85 are provided with notches, slots or embossings which are in 45 relation so as to produce a channel 86 in which is mounted a key as illustrated at 87 in Figure 19. In this engagement the key, lying in the opening formed by the two embossings, locks the two casings with respect to each other.

In Figures 20 to 23, I have illustrated a further modification of my invention. As shown in Figure 20, my reinforcing members may all be so shaped as to provide a rabbet at all edges, or, as has already been stated, in any combination of 55 these as desired. In this modification, as illustrated in Figure 22, the reinforcing members are all reversed in position when the container is collapsed in order to permit ready collapsing thereof and as heretofore, may be shipped with the 60 containers entirely separate.

In Figure 21, I have illustrated the turned in ends on both sides of the channel members for the purpose of more effectively gripping the material on both sides similar to that shown in Figure 15. An alternative method of providing a secure connection between the reinforcing members and the side walls is disclosed in Figure 23, in which the outer surface of the filler 78' 65 comprises adhesive 77, so that when the reinforcing member is slipped into place and pressed against the side wall, it may be adhesively secured thereto.

In Figure 24, I have shown for purposes of illustration the combination of drawer and casing 75 similar to that disclosed in my parent applica-

tion. It will be understood, however, that other construction of drawers than that herein illustrated as disclosed in my parent application may be used in connection with these casings. It will also be obvious that the casings may be used as 5 containers, bins, etc. without drawers.

Although I have disclosed preferred forms of reinforcing channels, it will be obvious that it might take other forms, as flat or longitudinally beaded metallic strips attached to the side walls. 10 Although I have disclosed a channel-shaped member as the preferred type of reinforcement members, both for the horizontal reinforcement members and for the vertical posts, it will be obvious that where the load is not so great, I may 15 use flat or longitudinally beaded metallic strips secured to the wall along the edges by any suitable means such as riveting and the like. Moreover, in the case of the upper and lower horizontal reinforcing members, I may use such flat 20 metal strips where the load requires channel-shaped posts, or combinations of metal edges and turn-in flaps, as shown in Figure 14.

Although I disclose rabbets formed by the vertical posts only, it will be understood that if desired, I may, as illustrated, form rabbets with the horizontal posts, or with both the horizontal reinforcing members and the posts, or in any combination which may be required.

Any or all of the U-shaped channels in the 30 forms described with or without rabbet formations may be shipped separately or unattached to be applied by the user.

It will now be understood that I have illustrated some of the forms my invention may take 35 and I do not wish to be limited thereby except as set forth in the appended claims.

I claim:

1. A casing for a file cabinet or the like, said casing having an open front end and comprising 40 a bottom wall; side walls; a top wall; said walls being made of sheet material having fold lines between the top, bottom and side walls along which lines the same is manually foldable to form said walls; reinforcing members at the front 45 edges of said bottom and top walls; vertical reinforcing members at the front edges of said side walls to produce greater compressive strength at the open front than that produced by the material in said side walls for carrying downward 50 stress of a load thereon, and means connecting horizontal and vertical reinforcing members to maintain rigid angular relationship; said casing being collapsible with the reinforcing members mounted thereon.

2. A casing for a file cabinet or the like having an open front side and comprising a bottom wall; side walls; a top wall; said walls being made of sheet material having fold lines between said top, bottom and side walls along which lines the 60 same is manually foldable to form said walls; metallic reinforcing members at the front edges of said bottom and top walls; and vertical metallic reinforcing members at the front edges of said side walls to produce greater compressive 65 strength at the open front than that produced by the material in the side walls, said vertical reinforcing members being interposed between and contacting said top and bottom wall reinforcing members for carrying downward stress of a load 70 thereon; said casing being collapsible with the reinforcing members mounted thereon.

3. A collapsible casing for a file cabinet having an open front end and comprising a bottom wall; side walls; a top wall; said walls being 75

made of sheet material having fold lines along which the same is manually foldable to form said walls; and reversible front edge reinforcing members, said members having a rabbet formation selectively lying in the interior of said casing to provide an abutment for a drawer front or exteriorly thereof; said casing being collapsible with the reinforcing members mounted thereon.

4. A collapsible casing for a file cabinet having an open front end and comprising a bottom wall; side walls; a top wall; said walls being made of sheet material having fold lines along which the same is manually foldable to form said walls; and front edge reinforcing members of channel formation, the front edges of walls of the casing being received in the channel, said reinforcing members having a rabbet formation selectively lying on the interior side of the casing or exteriorly thereof; said casing being collapsible with the reinforcing members mounted thereon.

5. A casing for a file cabinet or the like having an open front end and comprising a bottom wall; side walls; a top wall; said walls being made of sheet material having fold lines between the top, bottom and side walls along which lines the same is manually foldable to form said walls; metallic reinforcing members at front edges of said walls to produce greater compressive strength than that of the material forming said walls for carrying downward stress of a load thereon; and additional members for maintaining said reinforcing members in predetermined angular relation; said casing being collapsible with the reinforcing members and said additional members mounted thereon.

6. In casings to form a stack, a casing having an open front end and comprising a bottom wall; side walls; a top wall; said walls being made of sheet material having fold lines between said top, bottom and side walls along which lines the same is manually foldable to form said walls; adjacent walls being movable angularly relative to each other about said fold lines to permit the casing to be shipped in knock-down condition; front end reinforcing members for said walls of the casing including front edge metallic reinforcement for transmitting downward stress from casing to casing through the reinforcing members to the base of the stack and additional means carried by said reinforcing members for connecting and maintaining corresponding reinforcing members of adjacent casings in vertical alignment; said casing being collapsible with the reinforcing members and said additional means mounted thereon.

7. A casing having an open front end and comprising a bottom wall; side walls; a top wall; said walls being made of sheet material having fold lines between the top, bottom and side walls along which lines the same is manually foldable to form said walls; adjacent walls being movable angularly relative to each other about said fold lines to permit the casing to be shipped in knock-down condition; reinforcing members at front edges of said walls; an angle wire, one leg of which is secured to one of said reinforcing members, the other leg of said wire protruding from said reinforcing means, said angle wire being rotatable on said secured leg into position to be engaged by the reinforcing member of the adjacent edge for maintaining said adjacent walls in rigid angular relation.

8. In casings for a stack, each casing having an open front end and comprising a bottom wall; side walls; a top wall; said walls being made of

sheet material having fold lines along which the same is manually foldable to form said walls; adjacent walls being movable angularly relative to each other about said fold lines to permit the casings to be shipped in knock-down condition; reinforcing members at front edges of said walls, providing means for transmitting downward stress through the reinforcing members to the base of the stack; and angular metallic members held in place by reinforcing members of adjacent casings for selectively maintaining said walls in predetermined angular relation and interlocking said casings; said casing being collapsible with the reinforcing members mounted thereon.

9. An initially collapsible casing adapted to be shipped in knock-down condition, comprising a top wall; side walls; a bottom wall; channel reinforcing members clamped over the front edges of the top and bottom walls; corner angle members each having one leg inserted in the channel of one of said reinforcing members and adapted to be pivoted about said one leg; and channel reinforcing members adapted to be slipped over the front edges of the side walls and the other legs of said angle members in setting up the casing to maintain said reinforcing members and walls in predetermined angular relation; said casing being collapsible with the reinforcing members mounted thereon.

10. A casing member of the class described, comprising a quadrilateral box-like structure having a body formed of an integral blank of non-metallic material scored and folded along certain portions serving as corner edges between the top, bottom and side walls, said body having the forward end margins thereof faced with metal strips arranged to permit folding and unfolding of said box structure along said scorings, and means engaging the marginal metal strips for holding the walls of the casing member rigidly in right-angled relation.

11. A casing having an open front end and comprising a bottom wall; side walls; a top wall; said walls being made of sheet material having fold lines between top, bottom and side walls along which lines the same is manually foldable to form said walls; adjacent walls being movable angularly relative to each other about said fold lines to permit the casing to be shipped in knock-down condition, metallic reinforcing means secured at the open front end of said casing and adapted to reinforce said open front end and additional means on said reinforcing means to maintain adjacent walls of the said casing in rigid angular relation; said casing being adapted to be collapsed with the reinforcing and maintaining means secured thereto.

12. A casing having an open front end and comprising a bottom wall; side walls; a top wall; said walls being made of sheet material having fold lines between top, bottom and side walls along which lines the same is manually foldable to form said walls; adjacent walls being movable angularly relative to each other about said fold lines to permit the casing to be shipped in knock-down condition, metallic reinforcing means secured at the open front end of said casing and engageable with said top, bottom and side walls at said open front, and an angularly shaped wire arranged to cooperate with said metallic means to provide a substantially rigid predetermined angular relation between the walls of the file case at such open front; said casing being collapsible with said reinforcing means and wire mounted thereon.

13. A blank of sheet material for a collapsible casing with an open front, said blank having fold lines defining horizontal and vertical wall sections of said casing, said sections being manu-
5 ally foldable about said fold lines to form said casing; said vertical wall sections being united with and movable angularly relative to said horizontal wall section; metallic reinforcing means mounted on said blank to reinforce said casing
10 at said open front and means to maintain the walls of said casing in rigid angular relation to each other; said blank when assembled forming a collapsible casing, said reinforcing and maintaining means being mounted on said casing.
- 15 14. A casing for a stack having an open front end and comprising a bottom wall; side walls; a top wall; said walls being made of sheet material having fold lines between top, bottom and side walls along which lines the same is manu-
20 ally foldable to form said walls; adjacent walls being movable angularly relative to each other about said fold lines to permit the casing to be shipped in knock-down condition; vertical metallic reinforcing members having a portion se-
25 cured to side walls at said open front and another portion of said reinforcing members having a hollow-post formation for producing greater compressive strength than that of the material forming said walls for carrying downward stress
30 of a load thereon; and means interconnecting
- said reinforcing members for maintaining the walls of said casing in rigid angular relation, and for maintaining said reinforcing members of adjacent casings in vertical alignment.
- 15 15. In a collapsible casing having an open front end and comprising wall members united along fold lines extending from said open end; an angle wire, one leg of which is secured at the front edge of one of said walls, said angle wire being rotatable on said secured leg into position to be engaged at the front edge of the adjacent wall; means for holding said angle wire in place at said latter front edge for maintaining said adjacent walls in rigid angular relation. 5
16. In a collapsible casing having an open front end and comprising wall members united along fold lines extending from said open end; an angle wire, secured at the front edge of one of said walls; the portion of said angle wire so secured being continuous along the edge of said wall; said angle wire having a projecting leg at each end of the secured portion thereof; said angle wire being rotatable on said secured portion into position so that the projecting legs may be engaged at the front edges of adjacent walls; means for holding said angle wire in place at said latter front edges for maintaining said adjacent walls in rigid angular relation. 10 20 25
